UNITED STATES PATENT OFFICE.

HORATIO A. FOSTER, OF NEW YORK, N. Y., ASSIGNOR TO THE THOMSON-HOUSTON ELECTRIC COMPANY, OF CONNECTICUT.

HANGER FOR ELECTRIC LAMPS.

SPECIFICATION forming part of Letters Patent No. 449,153, dated March 31, 1891.

Application filed August 1, 1890. Serial No. 360,685. (No model.)

To all whom it may concern:

Be it known that I, HORATIO A. FOSTER, a citizen of the United States, residing in the city, county, and State of New York, have 5 invented a certain new and useful Improvement in Hangers for Electric Lamps, of which the following is a specification.

My invention relates to hangers for supporting electric-arc lamps. Its purpose is to 10 provide a cheap and simple device which may be readily attached to a building or other like support by being driven in or otherwise fastened to the wall of the building and guyed thereto.

15 The hanger is furnished with insulators for the lamp and conductors in circuit therewith, so that danger from the current at points within the building, as well as wasteful leakage, is avoided.

20 The accompanying sheet of drawings illustrates the preferred form of my improvement, in which—

Figure 1 is a perspective view showing the hanger as used and lamp suspended therefrom. Fig. 2 is a plan view of the outer portion of the hanger, and Fig. 3 a plan view of the metallic cap before bending the holding-leaves around the insulators. Fig. 4 shows in side elevation and vertical section the metallic cap, and Fig. 5 shows side and plan views of the collar for supporting and insulating the conducting-leads.

The hanger, which as a whole is designated by A, consists of a main rod or pole of considerable strength, which will be of varying length, according to the distance from the building at which the lamp is to be hung. The inner end of this rod is adapted to be fastened to the wall or other support, and is 35 herein shown sharpened to form a driving-tang, while at its outer extremity there is a cap-piece, from which the lamp is suspended. The rod may be of metal; but it usually is of wood with metallic end portions, the insulation thus gained being an additional safeguard against leaks to the building.

The cap-piece B has a socket b, into which fits the outer end of the hanger-rod, and four radiating leaves of malleable material c, (shown in Fig. 3,) each of which is bent into a

loop around a grooved insulator D of porcelain or other insulating material. In this way the insulators are firmly held in place, but can be individually replaced with ease if one or more become broken.

55 In the hanger shown there is provided, also, a collar E, (shown in detail in Fig. 5,) which encircles the rod and has two rings of malleable material bent around and holding insulators in the same manner as described above in connection with the cap-piece. Through these insulators pass the conductors leading to the lamp, and the purpose of this collar is to support as well as insulate these conductors.

65 The hanger is used in the following manner: The inner end of the pole is driven in or otherwise fastened to the side of the building, represented conventionally in Fig. 1 by the broken line x x. The lamp F is hung from 70 one of the insulators upon the cap-piece, and from others there extend guys H H, as many as necessary, which are herein shown connected to the wall at I.

75 It will be understood that the specific mechanical features described may be modified in various ways without avoiding the general nature of my invention, which consists in providing a light strong hanger adapted to be secured at one end to a building and guyed 80 thereto, the hanger being so provided with insulators that the lamp and conductors-leads, are all well insulated from the building.

85 What I claim as new, and desire to secure by Letters Patent, is—

1. The combination of the hanger for electric lamps, having one end fastened to a building or like support and provided with an insulated point of attachment for the lamp, with a guy wire or wires attached to and suspending its outer end by means of one or more insulators, as described.

90 2. A hanger for electric lamps, consisting of a rod or pole having a driving-tang at one end and a cap-piece at the other end, provided with insulators to which the lamp and supporting guy-wires are to be attached.

95 3. The hanger for supporting and insulating arc lights and conducting-leads, comprising a supporting rod or pole, a grooved closed

ring-insulator, and an attaching part having a socket embracing the pole and a malleable clamp bent around the insulator.

4. A hanger for electric lamps, consisting of a rod or pole provided with a driving-tang at one end, a cap-piece at its other end, having leaves of malleable material bent around and holding suitable insulators, and the collar having insulators through which the conductors leading to the lamps are adapted to pass.

5. The combination of the hanger-rod provided with a driving-tang at one end and insulators for insulating the lamp and conducting-leads from the building to which the hanger is to be attached, with the guy-wires for sustaining the outer end of the hanger, as described.

HORATIO A. FOSTER.
